UNITED STATES PATENT OFFICE.

OTTO L. HEMMING, OF NEW HAVEN, CONNECTICUT, ASSIGNOR TO THE F. B. SHUSTER COMPANY, OF NEW HAVEN, CONNECTICUT.

WIRE STRAIGHTENING AND CUTTING-OFF MACHINE.

1,121,100.

Specification of Letters Patent.

Patented Dec. 15, 1914.

Application filed March 20, 1913. Serial No. 755,680.

To all whom it may concern:

Be it known that I, OTTO L. HEMMING, citizen of the United States, residing at New Haven, in the county of New Haven and State of Connecticut, have invented certain new and useful Improvements in Wire Straightening and Cutting-Off Machines; and I do hereby declare the following to be a full, clear, and exact description 10 of the invention, such as will enable others skilled in the art to which it appertains to make and use the same.

My invention relates to wire straightening and cutting-off machines, and it consists of an arrangement of mechanism for driving all of the rotatable parts of the machine from one driving shaft or single belt drive.

Referring to the drawings wherein the 20 same figures of reference indicate like parts throughout the several views: Figure 1 represents an upper plan view of the head of a wire straightening and cutting off machine, and outside mechanism, connected therewith, and a broken view of the extension mechanism connected with the head; Fig. 2 is a side elevation looking in the direction of the arrow *a*, Fig. 1; and Fig. 3 is a front elevation and sectional view of 30 the extension mechanism looking in the direction of arrow *b*, Fig. 2.

1 is the driving shaft journaled in the brackets 2 and 3 projecting from the base 4 of the machine. This shaft is further supported by the portion 5 of bracket 2, Figs. 1 and 2, secured to the bracket 6 by the screw 7. The rear end of the wire straightening arbor 8 is journaled in the bracket 6, and its forward end in the machine head 9.

10 and 11 are tight and loose pulleys on the driving shaft. The forward end of this shaft carries the bevel pinion 12 to mesh with the bevel ring gear 13, secured to the 45 inner face of the balance wheel 14, rotatably mounted on the cam shaft 15.

16 is a sprocket wheel secured to the hub 17 of the balance wheel which is connected with the sprocket wheel 18, mounted on the 50 lower feed roll shaft 19, by the chain 20. The upper feed roll shaft 21 is rotated from shaft 19 by gears 22 and 23 in the usual manner of machines of this class. The in-

ner ends of these feed roll shafts carry the usual feed rolls 24 and 25.

26 is a large pulley, mounted on the driving shaft 1, and it rotates the straightening arbor 8 through the medium of the belt, or silent chain 27, connecting said large pulley with the small pulley 28, of the straightening arbor.

It will thus be seen that all of the moving parts connected with the machine-head are driven from a single shaft, or what may be termed, "a single belt drive," instead, as 65 before mentioned, of having a separate belt to drive the straightening arbor, a separate belt for the balance wheel pulley 14, and a separate belt for the feed roll shafts.

The balance wheel pulley, and the feed roll shafts are run continuously from the continuously running driving shaft 1, and when the incoming wire 29, Figs. 1 and 2, strikes the gage rod 30, located in the guide bar 31, said rod will actuate well-known mechanism located at the forward extension of the machine, but not shown, which mechanism will actuate the pivoted clutch lever 32, through the medium of the connecting wire 33 pulling in the direction indicated by the arrow *c*, to elevate the upper end 32^a of said lever, and release the key 34, which key will engage with the balance wheel 14 and temporarily bring the cam 85 shaft 15 into rotative engagement with the balance wheel and actuate the wire cutting-off lever 35, mounted on the rock shaft 36. At the completion of a revolution of the cam shaft, said shaft will be released and 90 brought to a standstill, and the feed rolls and straightening arbor will be driven independent of the cam shaft as before described. The clutch lever is journaled on the support 37, mounted in the end of the 95 boss 38, projecting from the machine-head.

All of the moving parts of the machine except the single belt driving feature, as represented by the driving shaft 1, and the means for connecting it with the rotatable 100 parts of the machine, are old and well known.

Having thus described my invention, what I claim is:—

The combination in a machine of the 105 character described having a straightening

arbor, feed-roll shafts, cam shaft, and its balance-wheel pulley, of a driving shaft, means for rotating said shaft, a pulley on said shaft for rotating the straightening arbor, a bevel gear carried on the inner face of the balance-wheel pulley, a bevel pinion on the end of the driving shaft meshing with the bevel gear, a sprocket wheel on the hub of the balance-wheel pulley and one on

one of the feed-roll shafts, and a sprocket 19 chain connecting said sprocket wheels.

In testimony whereof I affix my signature in presence of two witnesses.

OTTO L. HEMMING.
